TOY HELICOPTER

Eugene D. Messerschmidt, Omaha, Nebr.

Application April 30, 1956, Serial No. 41,281

Term of patent 14 years

(Cl. D34—15)

Fig. 1

Fig. 2

Fig. 3

Fig. 1 is a side elevational view of a toy helicopter, showing my new design;

Fig. 2 is a front elevational view thereof; and

Fig. 3 is a fragmentary perspective view thereof, part of the rotor being broken away for convenience in illustration.

I claim:

The ornamental design for a toy helicopter, substantially as shown and described.
